(57) **CLAIM**

The ornamental design for a tray table as shown and described.

DESCRIPTION

FIG. 1 is a perspective view of a tray table showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view showing the tray table in a folded position; and,

FIG. 10 is an enlarged view of a portion of the tray table within the area designated as 10 in FIG. 2.

The dashed broken lines in the drawings are for the purpose of illustrating portions of the tray table that form no part of the claimed design. The dot-dashed broken lines in FIG. 10 show the boundary of the enlarged view and forms no part of the claimed design.
